CLAIM

The ornamental design for a display screen with animated graphical user interface, as shown and described.

DESCRIPTION

1. Display screen with animated graphical user interface

1.1 is a front view of a first image in a sequence;

1.2 is a front view of a second image thereof;

1.3 is a front view of a third image thereof; and

1.4 is a front view of a fourth image thereof.

The broken lines showing a display screen form no part of the claimed design; the appearance of the transitional image sequentially transitions between the images shown in reproductions 1.1-1.4; the process or period in which one image transitions to another image forms no part of the claimed design.
